UNITED STATES PATENT OFFICE.

SUE M. VOORHEES, OF BRISTOW, VIRGINIA.

GARMENT.

Application filed November 7, 1921. Serial No. 513,482.

To all whom it may concern:

Be it known that I, SUE M. VOORHEES, a citizen of the United States, residing at Bristow, in the county of Prince William and 5 State of Virginia, have invented new and useful Improvements in Garments, of which the following is a specification.

This invention relates to improvements in garments and has more especial relation to 10 underbodies for children, such as is used for supporting pants, drawers and hose.

One of the objects of the present invention is the provision of an underbody which will adjust itself to the form of the wearer 15 and accommodate itself to either a narrow or broad shouldered person, permitting absolute free movement of the wearer without strain at any point.

Another object is the provision of an 20 underbody which is capable of adjustment so as to properly fit either a stout or thin child, or for adapting it to children of different sizes and thus reduce the number of different sizes necessary for manufacturers.

Another object is the provision of a body 25 of the above stated type, wherein the button band or reinforcing waist band, is of novel construction, the said band being formed of the material of which the body 30 is made, without cutting the material from the garment.

With the above and other objects in view, the invention further includes the following 35 novel features and details of construction, to be hereinafter more fully described, illustrated in the accompanying drawings and pointed out in the appended claims.

In the drawings, the figure shown is a 40 view of the outside of a garment constructed in accordance with the invention, the garment being spread out.

Referring to the drawings in detail, wherein like characters of reference denote corresponding parts, the body is shown as 45 being formed of separate complementary members 10, each of which comprises a body portion from which extends a breast strap 11 and a back strap 12, the material between these straps being cut away to accommodate 50 the arm pit, as shown at 13.

The breast strap of one member 10 and the back strap of the other member 10 is 55 connected by elastic tapes 14, which provide a strap for engagement over the shoulder of the wearer and these elastic tapes 14, together

with the breast and back straps form an arm hole for the passage of the arms.

The rear portions of each of the members 10 are removably and adjustably secured together. This securing means is in the form 60 of spaced buttons 15, which are carried by one member 10 and spaced button holes 16 formed in the other member 10, the said buttons and holes being under the waist line of the body so that the latter is connected 65 together only at this point. This permits of free relative movement of the upper back part of the section 10 and thus permits of a free movement of the wearer without binding at any point. It also permits the body 70 to accommodate itself to either a broad or narrow shouldered child.

The front portions of the section 10 are 75 adapted to be connected by means of buttons 17 and button holes 18.

By connecting the rear portions of the sections together in the manner stated, they may be relatively adjustable so as to increase or decrease the width of the garment and thus adapt a garment of one size for 80 children of different sizes. This materially reduces the number of different sizes necessary for the manufacture and sale of the garment.

The garment is preferably of a double 85 thickness and comprises an outer thickness 19 and an inner thickness 20 and in order to provide a reinforcing waist band, the outer thickness is folded over and this folded over portion is stitched along each edge so 90 as to provide a band 21 whose lower edge is spaced from the lower edge of the body. By forming the waist band 21 in this manner, it is not necessary to employ a separate piece of material or cut material of which the 95 band is formed, from the body.

The reinforcing band 21 also serves as a means for attaching buttons 22, by means of which the body may be used to support pants, or drawers, the said buttons 22 being 100 secured upon tapes 23, whose ends are stitched beneath the fold of the reinforcing band 21. It is also preferred to provide the neck and arm pit edges of the body with a facing 24, of tape or similar material which 105 is secured along the inside edges. In Figure 1 of the drawings, the body is shown as having attached thereto a pair of hose supporters 25, the latter comprising hose grips 26 which are secured at the outer ends of 110

tapes 27. The supporters 25 are adjustable in length through the medium of adjusting buckles 28.

In order to secure the hose supporters 25 to the body, there is provided a coupling which includes a body carried member 29 and a hose supporter carried member 30. The member 29 is shown as being provided with spaced parallel slots, one of which receives a tape 32 which is secured beneath the reinforcing band 21 after the manner of the tapes 23. The member 30 is secured to one end of an attaching tape 34, the latter being secured to one of the buckles 28.

It is preferred to provide two tapes 34 and the foremost of these tapes, that is the tape which is attached closest the front of the body is slightly shorter than the other tape so as to bring the hose supporter into proper position for attachment to the hose and equalize the strain. Each of the tapes 34 have secured thereto one of the members 30 and in addition, these members are provided with substantially T-shaped extensions, the heads 36 of which are adapted to be passed through the lowermost slot of the member 29. As this head is of greater length than the length of the slot, its ends will bear against the material at each end of the slot so as to hold the members coupled.

It is preferred to make the garment of sateen or other like material, which will not

require boiling when being laundered. The purpose of this is to prevent injury to the elastic tapes.

The invention is susceptible of various changes in its form, proportions and minor details of construction and the right is here-in reserved to make such changes as properly fall within the scope of the appended claims. 40

Having described the invention what is claimed is:

1. An undergarment comprising a body open at the front and back to provide separate body sections, shoulder straps having 45 their ends connected to the opposite ends of opposite sections, whereby the upper portions of the body sections will be relatively movable and a row of spaced horizontally arranged fastening devices located at the 50 waist of each body section of the garment to adjustably connect the sections.

2. A garment comprising a pair of body sections, each of said sections including a front and back, a shoulder strap extending 55 from the front and back of each section, the strap of one front being connected to the back of the other section and means connecting the backs of the sections at the waistline of the garment with the remaining adjacent portions of the back free.

In testimony whereof I affix my signature.

SUE M. VOORHEES.
